(57) **CLAIM**

I claim the ornamental design for the insect/fly screen, as shown, described, and illustrated.

DESCRIPTION

FIG. 1 is a front elevational view of an insect/fly screen embodying the present invention;

FIG. 2 is a rear elevational view thereof;

FIG. 3 is a fragmentary perspective view thereof;

FIG. 4 is a top plan view thereof;

FIG. 5 is a side view thereof;

FIG. 6 is an enlarged fragmentary side view thereof;

FIG. 7 is an enlarged fragmentary top plan view thereof; and,

FIG. 8 is an enlarged fragmentary sectional view taken along line 8—8 of FIG. 1.
